UNITED STATES PATENT OFFICE.

WALTER J. SCOTT, OF WOONSOCKET, RHODE ISLAND.

STOP MOTION FOR DRAWING FRAMES.

Application filed June 12, 1926. Serial No. 115,432.

This invention relates to an improved stop motion for drawing frames; and has for its object to provide in such a stop motion an electric circuit controlling lift bar extending longitudinally of one of the draft rolls and spaced therefrom, the bar being in an electric circuit whereby when the roving breaks and winds about the draft roll it builds up beneath the bar and raises the same to so affect the electric circuit as to stop the operating mechanism of the drawing frame.

A further object of the invention is to so arrange the mechanism that the raising of the lift bar makes a contact and completes the circuit to energize a motor and release a shift lever to throw the belt from the tight to the loose pulley to stop the machine.

With these and other objects in view, the invention consists of certain novel features of construction, as will be more fully described, and particularly pointed out in the appended claims.

In the accompanying drawings:

Figure 1 is an end elevation showing the roving as being fed through the machine and showing a portion of my improved stop mechanism positioned adjacent one of the draft rolls.

Figure 2 is a perspective view showing the contact bar as positioned adjacent the upper draft rolls and the contacts arranged to be engaged when either end of this bar is lifted to complete an electric circuit.

Figure 3 is a perspective view showing the belt shifting mechanism and the tripping mechanism which is electrically operated when the lift bar is raised into engagement with one of the contacts to complete the electric circuit.

Figure 4 is an enlarged view showing the lift bar as raised into engagement with the contact member by the winding of the roving about the roll.

Figure 5 is a diagrammatic view illustrating the electric wiring diagram and the electrically operating mechanism arranged to move the tripper to release the detent and permit the shift lever to move the belt from the tight to the loose pulley.

Figure 6 is a detail showing the notched end of the shift arm in released position to be engaged and reset by a resetting movement of the shift lever.

Figure 7 is a plan view showing the end of the tripper in section and showing the

detent arm in position to engage and cause the end of the spring pressed tripper to ride outwardly and then snap into the forked end of this arm.

Figure 8 is a detail side elevation showing the downwardly turned end of the tripper as engaging the slot in the end of the detent arm.

It is found in practice in the operation of such machines as worsted drawing machines and the like, of advantage to provide simple and effective means for stopping a machine when the roving breaks and begins to wind about its upper draft roll, which breaking often occurs and if the machine is not quickly stopped each time much yarn is wasted. My improved device is employed for the purpose of causing this roving as it starts to wind about the upper draft roll, to engage a lift bar which lies along and adjacent this roll to lift the same into engagement with the electrical contact to either close or open an electric circuit to release the belt shift lever to throw the belt from the tight to the loose pulley and so stop the machine, thus calling the attention of the attendant to at once repair the broken roving and start the machine into operation again; and the following is a detailed description of the present embodiment of my invention and showing one means by which these advantageous results may be accomplished.

With reference to the drawing, 10 designates one of the lower draft rolls and 11 one of the upper draft rolls between which the roving 12 is led to the flie 13 to be twisted and wound upon the bobbin 14.

In order to provide a simple and effective stop motion for arresting the action of the machine when this roving breaks and winds about the roll 11, I have positioned a relatively small bar 15 of light weight with its opposite ends guided in the brackets 16 to slide vertically therein.

In these brackets, I have mounted contact pins 17 which may be adjusted endwise and secured by a screw 18 in its post 19. To these posts 19 at either end of the bar I have connected the circuit wires 20 which posts 21 are connected together by a cross wire 21 to lead through the wire 22 to the battery 23 or source of current.

This bar 15 is also connected by another circuit wire 24 to the belt shift lever 25 which also serves as a conductor in the circuit, and the tripper arm 26 also serving as

another conductor through which the current passes through the contact 27 and wire 28 around to the solenoid magnets 29.

The tight main driving pulley 30 and the loose pulley 31 are mounted on the main drive shaft 32 of the machine and the belt (not shown) leading therefrom is engaged by the belt fork 33 which is mounted on the slide rod 34 which rod has a dog 35 fixed thereon to be engaged by a shift lever 36 pivoted at its lower end at the point 37. A coil spring 38 is arranged to act upon this shift lever 36 so that when released it will move the belt from engagement with the tight pulley 30 over to the loose pulley 31 to stop the machine.

In order to release this belt shift lever when the roving breaks and winds about the draft roll 11, the lift bar 15 is so arranged that as this roving builds up about this roll it lifts either one end or the other thereof into contact with the pin 17 and so completes the circuit through the mechanism above described to energize the solenoid 29 and to withdraw the tripper from engagement with the detent arm 25 permitting the spring 38 to act on this lever to throw the detent arm around into the position illustrated by the dotted line 40, in Figure 5 which at once releases this lever to throw the belt onto the loose pulley, and the extending end 39 of this detent arm is moved into the position illustrated in Figure 6 so that when this lever is again moved back into operating position it automatically swings the detent arm back into its operating position causing it to be engaged by the tripper lever 26 and the same is automatically set ready to repeat the operation whenever the roving is again wound about the roll to raise its bar and again complete the electric circuit.

Each set of draft rolls is equipped with a lift bar and set of contacts so that when any one of the rovings in the machine breaks the whole machine is stopped until the attendant repairs the roving and again starts the machine in motion as above described.

My improved stop motion is very simple and practical in construction, is inexpensive to manufacture and is effective in its operation to stop the machine whenever a roving is broken and winds about its draft roll.

The foregoing description is directed solely towards the construction illustrated,

but I desire it to be understood that I reserve the privilege of resorting to all the mechanical changes to which the device is susceptible, the invention being defined and limited only by the terms of the appended claims.

I claim:

1. In an electric stop motion for worsted drawing frames, the combination with an electric circuit, a stop motion in said circuit, a pair of draft rolls, a movable circuit closing element normally lying in proximity to, but clear of the working surface of the upper draft roll and above the path of the roving whereby a roving broken under a drafting strain is wound about said upper roll and this roving is built upon the outer surface thereof to engage and move said element to close said circuit and stop the machine.

2. In an electric stop motion for worsted drawing frames, the combination with an electric circuit, a stop motion in said circuit, a pair of front draft rolls, a longitudinally disposed circuit closer rod positioned in proximity to, but clear of, the working surface of the upper draft roll, and above the path of the roving whereby a roving broken under a drafting strain and wound about said upper roll will build up on the outer surface of said roll to engage and move said rod to close said circuit and stop the machine.

3. In an electric stop motion for worsted drawing frames, the combination with an electric circuit, a stop motion in said circuit, a pair of draft rolls, a circuit closure bar normally positioned in proximity to, but clear of, the working surface of the upper draft roll, and above the path of the roving, a pair of guide brackets in which the opposite ends of said bar are adjustably supported, a contact carried by said brackets, means for adjusting said contact to determine the extent of lift of said bar necessary for closing said circuit, whereby a roving broken under a drafting strain and wound about said upper draft roll is built up on the outer surface thereof to engage and move said bar to close said circuit and stop the machine.

In testimony whereof I affix my signature,

WALTER J. SCOTT.
